SECURITY ALARM SYSTEM

Kenneth H. Schmidt, Danbury, Conn., assignor to Mosler Research Products, Inc., Danbury, Conn., a corporation of Delaware

Filed July 10, 1957, Ser. No. 670,999
5 Claims. (Cl. 340—258)

My invention relates broadly to electronic security alarm systems, and more particularly to a transistorized, capacity-type alarm system, with an automatic self-supervisory circuit for non-operating periods of the alarm system.

One of the objects of my invention is to provide a capacity-type alarm system which provides protection and electronic supervision of the connecting lines between system units during non-operating periods of the capacity alarm system.

Another object of my invention is to provide a supervisory circuit for the connecting conductors between system units which is automatically switched into operation when the oscillator and resonant antenna circuits of the capacity-type alarm system are deenergized.

Another object of my invention is to provide a capacity-type alarm system in which the connecting lines between system units are under the constant supervision of an ultra-sensitive alarm producing relay during operating periods of my capacity-type alarm system.

Another object of my invention is to provide a capacity-type alarm system which goes into an alarm condition whenever the system is turned on, to notify the guard at the remote surveillance station that the area is ready to be secured.

Another object of my invention is to provide a capacity-type alarm system which goes into an alarm condition whenever the system is turned off in order to prevent unauthorized deenergizing of the system.

Another object of my invention is to provide a compact, self-powered, transistorized capacity-type alarm system.

A further object of my invention is to provide a capacity alarm system in which the components of the oscillator, antenna tuning, and detector circuits are under constant electronic surveillance in order to prevent any unauthorized tampering with the components of said circuits.

Other and further objects of my invention are set forth more fully in the specification hereinafter following by reference to the accompanying drawings, in which:

FIG. 1 is a simplified block diagram in schematic arrangement of my capacitance-type alarm system;

FIG. 2 is a perspective view of a typical installation of the capacity alarm system of my invention and particularly showing the construction of the antenna system and the manner in which a multiplicity of protected areas may be electronically observed at a remote central station;

FIG. 3 is an overall electrical schematic diagram of the capacity-type alarm system of my invention.

My invention is directed to the construction of an electronic security alarm system in which the objects under protection are connected in series and form an antenna system. The system operates on an electromagnetic principle. A transistor oscillator by means of the resonant antenna system radiates radio frequency energy into the area surrounding the antenna system, thus setting up an electromagnetic field of stored radio frequency energy.

An ultra-sensitive alarm relay circuit connected to the antenna resonating circuit through a detector circuit is balanced for the particular antenna system and the presence of any additional body or object in the electromag-

netic field will upset the balance of the relay circuit thus sending in an alarm since the amount of RF energy stored in the field has been changed.

The antenna resonating circuit is tuned so that any unauthorized tampering with the connecting lines between system units during operating periods will cause a current change in the balanced relay circuit thus throwing the alarm relay and initiating the alarm.

Whenever the system is turned on or off there is a current change in the balanced relay circuit of sufficient magnitude to cause the alarm to be initiated due to the system unbalance thus created.

During non-operating periods of the alarm system, that is, when the oscillator and antenna system circuits are deenergized, an independent supervisory circuit is automatically switched into the system which by-passes the oscillator, antenna tuning, and detector circuits and impresses a voltage across the connecting lines between the system units. Any tampering with the connecting line while the system is in this mode of operation will change the current to the balanced alarm relay circuit and cause an ammeter installed in that circuit to indicate an unbalanced condition. Thus the connecting lines between the units of the system are under protective surveillance during both operating and non-operating periods of the antenna system. This is also true of the oscillator, antenna tuning, and detector circuits since the housing in which they are encased is associated with a tamper switch which is in series with one of the connecting lines.

In referring to the drawings in more detail, similar numerals refer to similar components throughout this specification.

In FIG. 1 I have shown the basic block diagram of my capacity alarm system. It consists of: control unit 1; guard unit 2; and the objects, assembly, or area to be protected designated by reference character 3. Reference character 4 designates the antenna connection line connecting the control unit 1 to the insulated object or area under protection which forms the antenna system, while 5 and 6 refer to the conductors connecting guard unit 2 and control unit 1. Conductor 6 is grounded only at the control unit end to a cold water pipe ground 53, or other adequate grounding means.

The security alarm system of my invention is based on a change-in-capacitance principle, involving the proximity of the human body or some other object to a highly sensitive balanced antenna system, which is the safe and file cabinets themselves as shown in FIG. 2.

This system operates on an electromagnetic principle by transmitting radio frequency energy from control unit 2a into an antenna system, comprised in this particular illustration, of conductor 4a; file cabinets 7, 8 and 9; and safe 10. The cabinets and safe are insulated from ground by insulating blocks 11 and wired together at 12, 13, and 14 with heavy braid to complete the antenna circuit between the objects. The system is balanced for the particular safe and file cabinets or other objects or area under protection. Any additional object, such as a human being, placed in the sensitive area which entirely surrounds the safe, will change the amount of radio frequency energy stored in the field. This in turn will cause an unbalance in the alarm unit 2a, which is the guard unit for zone A.

This capacitance system may be either a single system installation or a multiple system installation as shown in FIG. 2. Here I have shown the guard units 2a, 2b, 2c and 2d of four separate systems installed at a common central station to enable one guard to maintain electronic surveillance over four separate removed areas. With this arrangement an intrusion in one of the protected

areas will indicate an alarm at its associated central station guard unit, thus "pin-pointing" the area of intrusion so the guard knows exactly where to take immediate action. The systems are not associated in any manner except that they may use a common guard unit power source.

I have shown the electrical wire schematic diagram of my invention in FIG. 3. The diagram is divided into two basic sections, the control unit 1 and the guard unit 2. The control unit is self-powered by one 1.5 volt dry cell type battery 15 which supplies B- voltage for said unit. Because a transistor is utilized in the circuit rather than a vacuum tube, this one battery will operate the system for approximately one year. The Day-Night switch 16 is connected in series with the power supply conductor 21. With switch 16 in the Night position, B- through conductor 22, after being filtered by by-pass capacitor 23, is suppressed on the transistor oscillator circuit which consists of oscillator transistor 17, base bias resistor 18, oscillator tank capacitor 19, oscillator transformer 20, and tank coupling capacitor 24. The RF output of this oscillator circuit is coupled by conductor 25 and coupling capacitor 26 to antenna desensitizing capacitor 27 in antenna lead-in conductor 4, antenna tuning capacitor 28, and one of the taps on the primary winding of detector transformer 29. Tuning capacitor 28 and the tapped primary winding of detector transformer 29 are in parallel and form the resonating circuit for antenna lead-in conductor 4 and antenna 3 (which consisted of file cabinets 7, 8, and 9, and safe 10 in FIG. 2). The antenna system is tuned or resonated by selecting the appropriate tap on the primary of transformer 29 and adjusting tuning capacitor 28 while observing tuning meter 30 as an indicating means for such procedure. The circuit is tuned so that there is a small voltage across the secondary winding of detector transformer 29. The sensitivity of the antenna system can be increased by changing the value of or removing desensitizing capacitor 27.

The detection circuit is comprised of the secondary winding of transformer 29; blocking capacitor 31; a rectifier circuit consisting of crystal diode 32 connected to ground and crystal diode 33 connected in series with the detector output conductor 34; and by-pass capacitor 35 to ground on the output of diode 33. The remainder of the control unit circuit consists of tuning meter 30 which is a micro-ampere meter, and tamper switch 36 connected in series with output conductor 34. Tamper switch 36 is positioned in the control unit in such a manner that it completes the control unit output circuit when the control unit housing is in place while the same circuit is opened when the control unit housing is removed. This is to prevent unauthorized tampering with the control unit components as will be discussed later. Ground line 6' in the control unit is grounded at the control unit.

Control unit output lines 34 and 6' are connected to conductors 37 and 6'', respectively, in guard unit 2 by connecting lines 5 and 6, respectively. Protection meter 38 is connected in series with conductor 37 and is a duplicate to tuning meter 30. This meter is placed in the guard unit so a guard at a remote location is assured that everything is in proper balance at the protected area, and no connecting lines, etc., have been tampered with. If one of the file cabinets, etc., had become disconnected or grounded during the Day period, the meter would not read in the safe portion of the meter scale when switch 16 is switched to the Night position. If the control unit housing or the connecting lines 5 and 6 were tampered with while switch 16 is in the Day position the meter would read in the unsafe portion of the scale but no change in meter indication will result from tampering with the antenna system components while this switch is in the Day position.

When switch 16 is switched to the Day position, B- excitation is removed from the oscillator circuit which results in deenergizing the antenna system and the detector circuit. B- is now applied to a supervisory circuit

which provides for the protection and supervision of the control unit housing and the connecting lines during the non-operating or Day periods of the alarm system. This supervisory circuit is comprised of switch 16 in the Day position, voltage drop resistor 50 and Day balance resistor 51, all in series with conductor 52 which connects to detector output conductor 34 between the junction of crystal diode 33 and by-pass capacitor 35, and tuning meter 30, thus inserting the supervisory circuit in series with tuning meter 30.

The principal portion of the guard unit circuit consists of the balanced alarm relay circuit which is composed of compensation capacitor 39 in series with ultra-sensitive alarm relay coil 40 shunted by load resistor 41 and also by by-pass capacitor 42. Movable contact arm 43 of the manual reset alarm relay is grounded. The alarm relay stationary contacts 44 are connected to one end of slave relay coil 45 while the other end is connected to B+. Movable contact arm 46 of the slave relay is connected to B+. Two alarm signals connected in parallel are provided at the guard unit, a buzzer 47 and a light 48. When the system becomes unbalanced and goes into alarm both alarm signals will indicate since slave relay contact control arm 46 impresses B+ across each. The buzzer can be silenced by means of silencer switch 49 but the light will not go out until the system is rebalanced and operating properly. To prevent the guard from forgetting to turn the buzzer back on, the silencer switch must be returned to the normal operating position when the unit is rebalanced or the buzzer alarm will indicate since in this state the slave relay contact arm 46 when it returns to its deenergized position impresses B+ across the buzzer if the silencer switch has not been returned to its normal operating position.

The light and buzzer indicators in the guard unit may operate from 115 volts A.C. power with a 6 volt stand-by battery so arranged that if the A.C. power supply should fail, all components of the guard unit would continue to operate without interruption since the stand-by battery supply would be switched into the circuit automatically. With switch 16 in the Night position a would-be intruder passing into or through the particular area under protection will change the amount of radio frequency energy stored in the field by the antenna system, since the system is balanced for the particular area under protection. This changes the capacity of the antenna system and results in a change in voltage across the secondary winding of transformer 29 and thus a change in control unit output current. The ultra-sensitive guard manual reset alarm relay responds to any change in current exceeding two micro-amperes, thus the above current change activates the alarm relay coil 40 which results in coil 45 of the slave relay being activated and impressing B+ across the alarm indicators by means of slave relay movable contact 46.

Since there is always a small voltage present across the secondary winding of transformer 29, if an unauthorized person opened the control unit housing the tamper switch 36 would break the output circuit, causing the current to drop to zero and this current change would throw the alarm relay, and through the chain reaction set forth above, the alarm would be activated.

The alarm will also be activated if the connecting lines between the control unit and the guard unit are cut, jumpered, or if the wire is bared and touched with the finger or a metal object, because each changes the current in the circuit sufficiently to instantly activate the alarm relay.

When the Day-Night switch is switched from Night to Day the oscillator is deenergized; thus the voltage across the secondary of transformer 29 disappears so the alarm is activated from the resulting current change or disappearance. This eliminates the possibility of an intruder turning off the alarm system since such a move sets off

the alarm. When it comes time to operate the system in the Day position the switching-over process will activate the alarm and the guard at his remote location being notified that it is an authorized system switch-over can manually reset the alarm relay thus deenergizing the alarms.

During Day position operation a B—D.C. voltage is impressed across the connecting lines 5 and 6 and any cutting or breaking of such lines or any opening of the control unit housing will result in the meters ceasing to indicate since they are in series with the tamper switch and connecting lines. No alarm is activated in this state since compensation capacitor 39 blocks the D.C. voltage and thus makes the alarm relay coil 40 insensitive to D.C. current changes.

Since during Day operation the antenna system (i.e. safe, file cabinets, etc.) is not under protection the objects or area of the antenna system may be touched and used as they customarily are during the day. Any damage to this section of the system during Day operation will not be discovered until the system is switched to Night operation.

When switch 16 in the control unit, which is located in the area under protection, is switched to the Night position the corresponding guard unit goes into alarm because of the current change from zero to some value. This notifies the guard at the guard unit that the control unit has been switched into Night operation. If during Day operation someone had purposely or accidentally damaged the system, such as breaking or cutting an antenna connection, grounding, or any break-down of internal components of the control unit, meters 30 and 38 would indicate in the danger zone, indicating a system unbalance. This would put the guard on notice of a failure in the system which must be corrected by "troubleshooting." If the guard unit meter indicates in the balanced zone, the guard at the guard unit secures the area by resetting the manual reset alarm relay, stopping the alarm and thus putting the system in operation until such time as the sensitive balance is upset by some cause. No warning signal is audible or visible in the secure area so that the would-be intruder setting off the alarm does not know he has informed the guard of his presence.

What I claim as new and desire to secure by Letters Patent of the United States, is as follows:

1. An alarm system comprising a control unit disposed in the area to be protected, a guard unit disposed in an area remote from the protected area, and two connecting lines electrically interconnecting said guard unit and said control unit, said control unit comprising a direct current power source, an oscillator circuit, a manually operated switch having first and second operative positions, said switch when in said first position being effective to interconnect said power source and said oscillator circuit, an antenna system connected to said oscillator circuit, an antenna tuning circuit connected with said antenna system, a detection circuit interconnected with said antenna system, the output leads of said detection circuit being interconnected to said connecting lines, a bypass line effective to interconnect said switch with one of said connecting lines when said switch is in said second operative position, whereby when said switch is in said first position said oscillator, said antenna system and said detection circuit are energized and apply an alternating current signal to said connecting lines, said signal being modified upon any intrusion into the protected area, and whereby when said switch is in said second position said oscillator is deenergized and a direct current signal is applied from said power source across said connecting lines which signal provides means at the guard unit for supervising said connecting lines, said guard unit comprising an ultra sensitive balanced arm relay circuit energized from said connecting lines, an alarm indicator energized in response to the actuation of said balanced arm relay, and indicating means responsive to current flow through said connecting lines.

75

2. An alarm system comprising a control unit disposed in the area to be protected, a guard unit disposed in an area remote from the protected area, and two connecting lines electrically interconnecting said guard unit and said control unit, said control unit comprising a direct current power source, an oscillator circuit, a manually operated switch having first and second operative positions, said switch when in said first position being effective to interconnect said power source and said oscillator circuit, an antenna system connected to said oscillator circuit, an antenna tuning circuit connected with said antenna system, a detection circuit interconnected with said antenna system, the output leads of said detection circuit being interconnected to said connecting lines, a bypass line effective to interconnect said switch with one of said connecting lines when said switch is in said second operative position, whereby when said switch is in said first position said oscillator, said antenna system and said detection circuit are energized and apply an alternating current signal to said connecting lines, said signal being modified upon any intrusion into the protected area, and whereby when said switch is in said second position said oscillator is deenergized and a direct current signal is applied from said power source across said connecting lines which signal provides means at the guard unit for supervising said connecting lines, said guard unit comprising an ultra sensitive balanced arm relay circuit energized from said connecting lines, an alarm indicator energized in response to the actuation of said balanced arm relay, and indicating means responsive to current flow through said connecting lines, the current change occurring upon shifting of said switch from one position to another being of sufficient magnitude to actuate said balanced arm relay.
3. An alarm system comprising a control unit disposed in the area to be protected, a guard unit disposed in an area remote from the protected area, and two connecting lines electrically interconnecting said guard unit and said control unit, said control unit comprising a direct current power source, an oscillator circuit, a manually operated switch having first and second operative positions, said switch when in said first position being effective to interconnect said power source and said oscillator circuit, an antenna system connected to said oscillator circuit, an antenna tuning circuit connected with said antenna system, a detection circuit interconnected with said antenna system, the output leads of said detection circuit being interconnected to said connecting lines, a bypass line effective to interconnect said switch with one of said connecting lines when said switch is in said second operative position, whereby when said switch is in said first position said oscillator, said antenna system and said detection circuit are energized and apply an alternating current signal to said connecting lines, said signal being modified upon any intrusion into the protected area, and whereby when said switch is in said second position said oscillator is deenergized and a direct current signal is applied from said power source across said connecting lines which signal provides means at the guard unit for supervising said connecting lines, said guard unit comprising an ultra sensitive balanced arm relay circuit energized from said connecting lines, an alarm indicator energized in response to the actuation of said balanced arm relay, and indicating means responsive to current flow through said connecting lines, the current change occurring upon shifting of said switch from one position to another being of sufficient magnitude to actuate said balanced arm relay.
4. An alarm system comprising a control unit disposed in the area to be protected, a guard unit disposed in an area remote from the protected area, and two connecting lines electrically interconnecting said guard unit

and said control unit, said control unit comprising a housing enclosing a direct current power source, an oscillator circuit, a manually operated switch having first and second operative positions, said switch when in said first position being effective to interconnect said power source and said oscillator circuit, an antenna system connected to said oscillator circuit, an antenna tuning circuit connected with said antenna system, a detection circuit interconnected with said antenna system, the output leads of said detection circuit being interconnected to said connecting lines, a normally closed tamper switch mounted within said housing, said switch having contacts in one of said output lines and being adapted to open upon opening of said housing, a bypass line effective to interconnect said switch with one of said connecting lines when said switch is in said second operative position, whereby when said switch is in said first position said oscillator, said antenna system and said detection circuit are energized and apply an alternating current signal to said connecting lines, said signal being modified upon any intrusion into the protected area, and whereby when said switch is in said second position said oscillator is deenergized and a direct current signal is applied from said power source across said connecting lines which signal provides means at the guard unit for supervising said connecting lines, said guard unit comprising an ultrasensitive balanced arm relay circuit energized from said connecting lines, an alarm indicator energized in response to the actuation of said balanced arm relay, and indicating means responsive to current flow through said connecting lines. 30

5. An alarm system comprising a control unit disposed in the area to be protected, a guard unit disposed in an area remote from the protected area, and two connecting lines electrically interconnecting said guard unit and said control unit, said control unit comprising a direct current power source, an oscillator circuit, a man- 35

ually operated switch having first and second operative positions, said switch when in said first position being effective to interconnect said power source and said oscillator circuit, an antenna system connected to said oscillator circuit, an antenna tuning circuit connected with said antenna system, a detection circuit interconnected with said antenna system, the output leads of said detection circuit being interconnected to said connecting lines, a meter in one of said output leads, a bypass line effective to interconnect said switch with one of said connecting lines when said switch is in said second operative position, whereby when said switch is in said first position said oscillator, said antenna system and said detection circuit are energized and apply an alternating current signal to said connecting lines, said signal being modified upon any intrusion into the protected area, and whereby when said switch is in said second position said oscillator is deenergized and a direct current signal is applied from said power source across said connecting lines which signal provides means at the guard unit for supervising said connecting lines, said guard unit comprising an ultrasensitive balanced arm relay circuit energized from said connecting lines, an alarm indicator energized in response to the actuation of said balanced arm relay, and a meter responsive to current flow through said indicators. 25
